IMPROVED BUCKLE.

ANGELINE BUTTON, ADMINISTRATRIX OF CHARLES A. BUTTON, DECEASED,
OF PONTIAC, MICHIGAN.

Letters Patent No. 60,185, dated December 4, 1866.

SPECIFICATION.

TO ALL WHOM IT MAY CONCERN:

Be it known that CHARLES A. BUTTON, late of Pontiac, in the county of Oakland, and State of Michigan, did, in his lifetime, invent an Improved Buckle, intended more especially for harness and leather straps; and I, ANGELINE BUTTON, of the same place, administratrix of the estate of the deceased, do hereby declare that the following is a full and exact description thereof, reference being had to the accompanying drawings, making part of this specification—

Figure 1 being a side edge view of the buckle.

Figure 2, a top view thereof.

Figure 3, a central longitudinal section thereof.

Like letters designate corresponding parts in all of the figures.

The body, or rim, A, of the buckle has, just forward of the chape, B, a bar, or jaw, *h*, against which one side of the strap, *w*, is gripped by a jaw, *g*, of the clasp C, there being no tongue used. The pinching surface of this jaw may be grooved or roughened, if desired, though not necessarily. This clasp, C, has journals, *i i*, (fig. 1,) which enter into hook bearings, *ff*, on the sides of the rim, A, of the form substantially as shown, so that the clasp can be readily removed when the strap or tug, *w*, is not in the buckle, but cannot be accidentally removed when the strap is in place. On the opposite edge of the clasp from the jaw, *g*, is a cross-bar, *d*, substantially as shown, against which the strap or tug bears, and from its leverage, acting by the pivot journals, *i i*, causes sufficient compression of the jaw, *g*, on the strap to hold it from slipping. The tighter the strap is drawn the more powerful is this leverage pressure, and, consequently, the more securely does the buckle hold. The front bar of the rim, A, between which and the cross-bar, *d*, the strap is drawn, assists not only in keeping the strap in place, but in increasing the pressure of the strap on the clasp. The buckle will act either on a thin or thick strap, the space between the jaw, *h*, and the throat-bar, B, being, in a large harness buckle, wide enough to admit a strap half an inch thick. There may be side-fenders, *a a*, to strengthen and protect the journal bearings, *ff*. The buckle may be made quite ornamental in form, and finished in any style.

What I claim as the invention of CHARLES A. BUTTON, deceased, is the combination of the clasp C, and body or rim A, constructed and connected substantially as and for the purpose herein specified.

The above specification of CHARLES A. BUTTON's improved buckle signed by me this 30th day of August, 1866.

ANGELINE BUTTON.
